Atty

UNITED STATES PATENT OFFICE.

DONALD B. RUSH, OF VILLA PARK, ILLINOIS, ASSIGNOR TO ROBERT W. HUNT COMPANY, A CORPORATION OF DELAWARE.

GRADING MACHINE FOR GRANULAR MATERIAL.

Application filed January 9, 1924. Serial No. 685,153.

To all whom it may concern:

Be it known that I, DONALD B. RUSH, a citizen of the United States, residing at Villa Park, county of Du Page, State of Illinois, have invented a certain new and useful Improvement in Grading Machines for Granular Material, and declare the following to be a full, clear, and exact description of the same, such as will enable others skilled in the art to which it pertains to make and use the same, reference being had to the accompanying drawing, which forms a part of this specification.

The present invention has for its object to produce a simple and novel machine for quickly and effectively sifting comminuted solids, particularly those that are in a finely divided or powdered state, for the purpose of grading the same.

The various features of novelty whereby my invention is characterized will herein-after be pointed out with particularity in the claims; but for a full understanding of my invention and of its objects and advantages, reference may be had to the following detailed description taken in connection with the accompanying drawing, wherein:

Figure 1 is a perspective view of a machine arranged in accordance with a preferred form of my invention, employing four pans or sieves, two of which are omitted from the drawing; Fig. 2 is a vertical transverse section through the machine; Fig. 3 is a vertical section, on a somewhat larger scale, taken at right angles to the plane of Fig. 2 through one of the upper corners or edges of the machine; and Fig. 4 is a top plan view of one corner of the machine, showing one of the pans or sieves.

The sifting or grading is done in cylindrical pans or receptacles 1, each of which has a removable screen 2 extending transversely across the same between the top and bottom. These devices are in common use and may therefore be said to be of any usual or suitable construction. In grading very finely divided material such as ordinary dry powdered cement, for example, the screen must be very fine, having a mesh of perhaps two hundred to the inch. In order to make this very fine material pass through the screen, the pan must be jarred and shaken, this being a tedious operation when performed by hand.

In accordance with the present invention, any desired number of pans are simultaneously jarred and shaken by power-actuated mechanism and, at the same time, are given a rotary movement which prevents the material on the screens from piling up in a heap first on one side and then on the other side of each pan.

Any desired number of pans are set loosely in recesses or pockets 3 opening out of the top of a suitable table 4, but extending only part way through the table. The pans are cylindrical and the recesses or pockets are also preferably made cylindrical but somewhat larger in diameter than the pans, so that the pans may move about in the pockets or recesses.

The pockets or recesses are lined with a suitable cushioning material 5, this lining extending around the sides and also, if desired, across the bottom of each pocket. It will thus be seen that if the table is rapidly oscillated in the direction of its length or width, the pans will be shaken and jarred, due to the fact that they continue their movements until arrested by bumping against the sides of the pockets, whenever the table reaches either end of a stroke and stops before starting on a return stroke. The table is supported upon the open top of a box or casing 6 and thus forms a cover for the casing. The table and the casing may both be made rectangular, so that the table may conveniently be supported on rails 7 arranged along the upper edges of two opposite sides of the casing, by means of suitable wheels 8 journaled on the table. The table therefore forms a carriage that may be moved back and forth along the rails with the exertion of a minimum of effort. Within the casing is arranged a small motor 9 provided with a flexible shaft 10 on which is fixed a worm 11 that meshes with a worm wheel 12 fixed to a suitable shaft 13 that is in turn rotatably mounted in suitable bearings. There is also fixed to the shaft 13 a crank or disk 14. A bracket 15 is fixed to and projects down from the under side of the table; and between the bracket and the disk or crank is a connecting rod 16. The parts are so arranged that the connecting rod operates in a vertical plane parallel with the rails or tracks on which the table is supported so that, when

the motor is running, the table will be rapidly reciprocated. The flexible section of the motor shaft, which is preferably in the form of a coiled spring, not only compensates for any slight inaccuracy in the alignment of the various parts of the mechanism, but it also cushions the blows or shocks to which the motor might otherwise be subjected.

10 The motor will ordinarily be operated at a high speed and therefore, in order to keep the same, and also the gearing, reasonably cool, the side walls of the casing are provided with openings 17 near the base of the 15 casing, and the motor shaft is provided with a fan element 18, so that a constant stream of air is caused to flow through the casing while the motor is running, and the mechanism is thus prevented from overheating.

20 The reciprocation and jarring of the pans that result from the operation of the table are not sufficient to produce the best results, because the material in each pan tends to pile up first on one side and then on the 25 other as the pan moves back and forth. If a pan be rotated at the same time that it is shaken back and forth, all parts of the screen therein come into play and the shifting of the contents becomes more rapid and 30 effective. In order to secure the necessary rotary movement of the pans, without employing any complicated mechanism or attachments, and without making it necessary to fasten the pan to anything, I have made 35 use of the simple expedient of two small buttons 19 and 20 projecting inwardly from the sides of each pocket or recess in the table. These buttons or projections are preferably placed diametrically opposite each 40 other, on opposite sides of a vertical plane passing through the center of the pocket or recess and parallel with the supporting tracks or rails for the table; the diameter connecting said buttons or projections making 45 an acute angle with said plane; and the distance between the buttons or projections being considerably greater than the diameter of the pan.

Assuming the table to be reciprocated in 50 the direction of the double arrow A in Fig. 4, it will be seen that as the pan strikes the button 19, the pan will be turned in the counter-clockwise direction through more or less of an angle. This occurs during a 55 stroke of the table in one direction. During the next stroke, in the opposite direction, the pan strikes the button 20 and is thus given a further angular movement in the same direction as before. The result is 60 that each pan is turned step by step while it is being reciprocated in the manner herefore described.

The buttons or projections for turning the 65 pans or sieves are preferably made of rubber or other cushioning material so as to

eliminate noise and also to enable them to grip the pans more or less when they come forcibly into contact with the latter.

It will thus be seen that I have produced a simple and novel mechanism by which 70 any desired number of individual detached pans or sieves, of any desired construction, may simultaneously be jarred, shaken and rotated; without requiring any other attention on the part of the user, in order to insure rapid and efficient sifting or grading, 75 than is needed to start and stop the motor.

It will also be seen that I have produced a simple and novel operating mechanism 80 for the table that carries the pans and sieves, normally enclosed in a housing but rendered accessible for inspection or repairs by the mere act of swinging the table up without disconnecting it from the operating mechanism.

While I have illustrated and described with particularity only a single preferred form of my invention, I do not desire to be limited to the exact structural details thus illustrated and described; but intend to cover all forms and arrangements which come within the terms employed in the definitions of my invention constituting the appended claims.

I claim:

1. A machine of the character described comprising a support, a circular sieve resting loosely on said support, means for limiting the movement of the sieve relative to said support, means for reciprocating said support, and stops on said support in front of and behind the sieve and spaced apart a distance greater than the diameter of the sieve, said stops being arranged on opposite sides of a line passing through the center of the sieve in the direction of reciprocation, whereby the sieve will be given a step-by-step rotary movement as well as a shaking or jarring when said support is reciprocated.

2. A machine of the character described comprising a casing open at the top, a table extending across the top of the casing and supported by the latter for reciprocatory movements in the plane thereof, a circular sieve resting loosely on said table, means for limiting the movements of the sieve across the table, mechanism in the casing for reciprocating said table, and stops so positioned on the table that the sieve will strike against them and be turned step by step as the table is reciprocated.

3. A machine of the character described comprising a table having in the top a series of pockets or recesses, circular sieves resting in said pockets or recesses and each having such a diameter that it may move bodily a limited distance across the table, and two projections located in each pocket or recess at opposite sides thereof and spaced apart farther than the diameter of the correspond-

ing sieve, the projections in the several pockets or recesses being similarly positioned.

4. A machine of the character described comprising a casing open at the top, a table resting loosely upon and supported by said casing, sifting means carried by the table, power mechanism including a crank member arranged in said casing, and a connecting rod extending between said crank member and said table to reciprocate the latter, the parts being so proportioned and arranged that the table may be lifted from the casing to expose said power mechanism without unfastening the connecting rod.

5. A machine of the character described comprising a casing, a table resting on said casing and movable across the top of the same, sifting means including a receptacle for containing the sifted material carried by said table, a motor within said casing, a crank member in the casing and a connecting rod between the same and said table, and a speed-reducing gearing including a flexible resilient shaft between said motor and said crank member.

6. A machine of the character described comprising a casing, a table resting on said casing and movable across the top of the same, sifting means carried by said table, a motor within said casing, a crank member in the casing and a connecting rod between the same and said table, a speed-reducing gearing including a flexible resilient shaft be-

tween said motor and said crank member, a fan on said motor shaft, and there being openings through the sides of the casing to permit the fan to cause a current of air to flow through the casing when the motor is running.

7. A machine of the character described comprising a casing, a table resting on said casing and movable across the same, sifting means carried by said table, power mechanism in the casing for reciprocating said table, a fan associated with said power mechanism, and there being openings through the walls of the casing to permit the fan to cause a current of air to flow through the casing while said power mechanism is in operation.

8. A machine of the character described comprising a casing open at the top, parallel rails on the casing, a table overlying the top of the casing and having wheels resting on said rails, said table having a series of pockets extending partly through the same from the upper face, circular sieves considerably smaller in diameter than the pockets resting loosely in the latter, power mechanism in said casing for moving said table back and forth along said rails, and means in said pockets for engaging with said sieves and turning them step by step as the table is reciprocated.

In testimony whereof, I sign this specification.

DONALD B. RUSH.
